FISHING DEVICE FOR OIL WELLS

Russell H. Giese, Oklahoma City, Okla., assignor to Bess L. Reed, Wichita, Kans.

Application February 28, 1935, Serial No. 8,758
Renewed July 20, 1937

11 Claims. (Cl. 294—68)

The invention relates to fishing devices for use in oil or other deep wells for removing from the well parts of drilling apparatus or junk which may have become detached or broken off or may be otherwise present in the well.

An object of the invention is to provide a fishing device having a large basket or chamber for receiving the parts of drill apparatus or junk of substantial size, while maintaining ample size and strength in the body of the fishing tool to carry the requisite amount of weight to the drilling bit to cut and break the steel junk on the bottom.

Other objects will appear hereinafter.

The invention consists in the features, combination, and arrangement of parts hereinafter described and particularly pointed out in the claims.

In the drawing:

Fig. 1 is a side elevation of the basket tool embodying the invention.

Fig. 2 is a horizontal section on line 2—2 of Fig. 1 through the lower part of the body above the beveled bottom of the basket or chamber.

Fig. 3 is a view of the body of the tool with the sleeve removed, looking from the left of Fig. 1.

Referring to the drawing, 1 represents the body of the basket tool or device which is a solid casting or forging provided with threads at its ends for connection to the drill stem and drill bit or milling tool, not shown. In the embodiment shown, the upper end of the basket fishing tool body 1 is provided with an internally threaded bore or box connection 2 to connect with the drill stem while at its lower end the body 1 is provided with a threaded pin connection 3 to carry the drill bit or milling tool.

The drill bit or milling tool cuts and breaks up the junk into pieces which pieces are pushed upward off the bottom by the rotating tool and by the flushing fluid, and these pieces fall into the basket of the fishing tool.

The upper part 4 of the body 1 is cylindrical, providing an area to be engaged by tongs in tightening or unscrewing the body 1 from the drill stem. Below the cylindrical portion 4, the body is offset in respect to the axis of rotation and is substantially semi-circular in cross-section, as shown at 5, and is continued in semi-circular shape and offset relation down towards the lower end of the body where a full round shape 6 is assumed coaxial with the axis of rotation and the upper cylindrical part 4, from which round portion 6 the threaded pin connection 3 extends.

55 The full round lower body portion 6 is slightly

greater in radius than the semi-circular intermediate body portion 5, so that an annular shoulder is provided at 7. Just at this point also, the intermediate body portion 5 is made of full round shape of the radius of the major semi-circular portion thereof as shown at 5a. This holds in position against lateral movement a section of pipe 8, the inside radius of which is the same as the radius of the semi-circular body portion 5 and the full round lower part 5a thereof. The 10 piece of pipe 8 may be cut to any desired length within that of the semi-circular body portion 5, and may be beveled at the top as shown at 9. This piece of pipe 8 is dropped over the top end of the tool and fits over the round portions 5a and 15 is thus retained in position in contact with the wall of the semi-circular body portion 5, the lower end of the pipe resting on the annular shoulder 7. In this position the pipe is preferably welded to the body at any convenient point to hold it in 20 position against axial and rotary movement. The weld is indicated at 9a.

The upper and lower cylindrical portions of the tool body are provided with a central bore 10 and a pipe 11 is placed in the bore and carries flushing fluid through the tool to the bottom. The central bore 10 takes the form of a groove 10a in the semi-circular body portion 5, and the pipe 11 occupies the groove. The pipe 11 is bellied out slightly at its top as shown at 11a so that it will 25 not drop through the tool, and is preferably welded to the body at its bell portion 11a. The pipe 11 may be of any desired inside diameter 30 suitable to give sufficient volume and a nozzle or jet effect of the flushing stream.

The solidity and strength of the basket tool according to the present invention is readily apparent in the provision of the solid semi-circular body portion 5, which, at the same time, provides a basket chamber of substantial semi-circular 40 shape adapted to readily receive large pieces of junk or parts of drilling apparatus. The intermediate body portion 5 is enlarged near its ends to substantially circular shape in joining the terminal cylindrical portions 4 and 6, the beveled 45 portions 5c and 5d forming a continuation of the flat face of the body portion 5. A solid tool body 1 is thus provided of substantial strength from end to end of the tool, amply capable of sustaining any amount of weight required to cut and 50 break up steel junk in the bottom of the hole.

It will be readily apparent to those skilled in the art that this arrangement of parts forms a chamber of considerable depth and may be of any desired depth, and the chamber is substan- 55

tially the radius of the tool in the smallest width dimension of the chamber. This chamber is large enough in any given size of apparatus to receive a full size reamer cutter of the size reamer used in the bore hole in which the tool may be run, and such cutter can be fished out without the necessity of cutting it up. The tool is, of course, made in any convenient size as to diameter or length.

10 In operation, a drill bit or milling tool is screwed into or on the lower end of the body, which has sufficient strength in the solid semi-circular body portion so that any desired amount of weight may be imposed on the drilling bit to cut and break the steel junk on the bottom, usually embedded in mud fluid. The rotation of the drill bit and tool pushes the junk off the bottom and up along the sides of the bore hole, the flushing fluid circulation assisting, and as this junk is moved 15 upward and comes opposite the recessed side of the tool there is a natural tendency of the mass to move inwardly over the mouth of the chamber, and the heavy junk, usually steel, falls by gravity into the chamber.

20 25 With this construction no difficult manipulation is required to get the junk into a restricted side opening, as in the case of side-door basket tools, but due to the open semi-circular space extending the full length of the semi-circular body, the junk 30 naturally moves inward into the space in position to drop into the open upper end of the pipe forming the chamber.

35 The body portion I at its inner face is flat and is partly surrounded by the shell forming in part the receptacle or basket into which the parts to be recovered enter, the said flat face or side constituting a wall of this basket or receptacle. The receptacle is therefore defined by the shell portion and by the flat face. Said receptacle is 40 open at its top.

I claim:

45 1. A fishing tool comprising a body having thread connections at either end, a fluid passage-way from end to end, the middle body portion being offset to one side of the axis of rotation and a shroud about a portion of the offset and forming a chamber opening upwardly.

2. A fishing tool including a body having a middle portion positioned eccentric to the axis of rotation, a shoulder formed on the body, a sleeve resting on the shoulder and surrounding part of the middle portion forming a chamber opening upwardly and a fluid conduit through the tool.

50 55 60 65 3. A fishing tool for deep wells having an upper terminal portion and a lower terminal portion of larger diameter than said upper portion, and axially in line therewith, an intermediate body portion connecting the terminal portions and arranged off to one side of the axial line of said upper and lower portions, and a basket portion carried by the larger diameter lower portion and extending up therefrom with its vertical wall at a greater radial distance from the vertical axis of the tool than the side face of the upper terminal portion, said basket portion being open at its top and surrounding a part of the space between the upper and lower terminal portions provided by the offsetting of the body portion, substantially as described.

70 75 4. A fishing tool having upper and lower terminal portions in axial alignment and a solid body portion connecting the terminal portions and offset laterally in relation to the vertical axis of the tool, the inner side of said body portion being substantially flat and substantially in the

diametrical plane of the tool, and a basket comprising a shell portion open at its top to the space adjacent the flat side of the body, and together with the said flat side defining a receptacle for the material to be recovered.

5 10 15 5. A fishing tool comprising a body having terminal portions in axial alignment, an intermediate body portion eccentrically disposed in respect to the axis of said terminal portions and providing a receiving space between said terminal body portions, and a sleeve embracing the eccentric intermediate body portion and being coaxially disposed with respect to the axis of said terminal portions to enclose a portion of said receiving space.

15 20 25 30 35 6. A fishing tool comprising a body having terminal portions in axial alignment, an intermediate body portion eccentrically disposed in respect to the axis of said terminal portions and providing a receiving space between said terminal body portions, an upwardly facing annular shoulder between said intermediate body portion and the lower of said terminal portions, and a sleeve resting on said shoulder and embracing the eccentric intermediate body portion, said sleeve being of less length than the intermediate body portion and being coaxially disposed with respect to the axis of said terminal portions to enclose the lower portion of said receiving space and to form a basket or receiving chamber opening upwardly into said receiving space.

40 45 50 55 60 65 7. A tool of the character described having upper and lower terminal portions axially in line, a body portion connecting the terminal portions, and offset relative to the vertical axis of the tool, and having a flat inner face substantially in a plane passing through said axis, and a shell portion opposite to and spaced apart from the said flat face and extending from the lower terminal portion part way of the height of said body portion, and presenting an opening for the entrance of material to be recovered into the receptacle defined by the spaced apart shell and flat face.

70 75 8. A fishing tool comprising a body having circular terminal portions in axial alignment and a segmental shaped intermediate body portion eccentrically disposed in respect to the axis of said terminal portions and providing a complementary segmental shaped receiving space opposite thereto and between said circular terminal portions, the lower end of said segmental shaped intermediate body portion being enlarged to circular shape adjoining and coaxial with but of less diameter than the lower circular terminal portion to provide an upwardly facing shoulder, and a sleeve resting on said shoulder and embracing the eccentric intermediate body portion and the lower portion of the complementary segmental shaped receiving space to form a basket or receiving chamber opening outwardly into the upper portion of said receiving space.

85 90 95 100 9. A fishing tool comprising a body having circular terminal portions in axial alignment and a substantially semi-circular intermediate body portion eccentrically disposed in respect to the axis of said terminal portions and providing a complementary substantially semi-circular receiving space opposite thereto and between said circular terminal portions, a flushing fluid conduit extending through a bore in said terminal body portions and disposed in a groove in the face of said substantially semi-circular body portion, said groove forming a continuation of said bore, and a sleeve coaxial with said terminal portions embracing the lower part of said semi-circular

body portion and enclosing the lower part of said semi-circular receiving space to provide a basket or receiving chamber opening upwardly into the upper part of said receiving space.

- 5 10. A fishing tool according to claim 9 in which the lower end of said semi-circular intermediate body portion is enlarged to circular shape adjoining and coaxial with but of less diameter than the lower circular terminal portion to provide
10 an upwardly facing shoulder, said sleeve resting on said shoulder and embracing said circular en-

largement and being retained against lateral movement thereby.

11. A fishing tool according to claim 9 in which the upper and lower ends of said semi-circular intermediate body portion are enlarged to circular shape adjoining the circular terminal portions, said enlargements including beveled portions substantially forming continuations of the flat face of the semi-circular body portions. 5
